UNITED STATES PATENT OFFICE

116,141

DESIGN FOR SUNGLASSES

Gerardo F. Marciano, Providence, R. I., assignor
to Universal Optical Corporation, a corpora-
tion of Rhode Island

Application August 5, 1938, Serial No. 79,129

Term of patent 3½ years

To all whom it may concern:

Be it known that I, Gerardo F. Marciano, a citizen of the United States, residing at Providence, county of Providence, and State of Rhode Island, have invented a new, original, and ornamental Design for Sunglasses of which the following is a specification, reference being had to the accompanying drawing, forming a part thereof.

Fig. 1 is a front elevation;

Fig. 2 is a side elevation; and

Fig. 3 is a section on line 3—3 of Fig. 1, showing my new design for sunglasses.

The distinctive features of my new design reside in the lens parts having their widest portions adjacent to the point of attachment of the temples; also in the continuous curved surfaces extending from adjacent the nose pads and bridge part to the point of attachment of the temples; also in the contour of the temples and in the substantial difference in width of the temple relative to the width of the lens at their point of attachment.

I claim:

The ornamental design for sunglasses, substantially as shown and described.

GERARDO F. MARCIANO.
